AXLE JOURNAL BEARING

Victor Alexander Bary, London, England

Application October 14, 1932, Serial No. 637,930
In Germany October 24, 1931

22 Claims. (Cl. 308—38)

In axle bearings with top and bottom liner shells the arrangement of the bottom shell involves great difficulties, especially if it is to be made adjustable. It has already been proposed to suspend the bearing liners, in hinge-fashion, from bearing eyes on the housing or on the upper shell and to mount the lower shell on the hinge bolts, the adjusting members being, in some cases, interposed. This method of mounting has the disadvantage that the forces to be taken up are conveyed only by indirect means to the housing so that, in the transference of such forces parts are called into play which, as regards their structural form and their arrangement, are unsuited to receive and transmit percussive forces which attain considerable magnitude. Changes of shape take place, for instance, deformation of the hinge bolts, which not only upset the predetermined arrangement of the parts but also, to some extent, defeat their function and make their subsequent removal and insertion difficult or possible only by destroying the parts concerned.

The present invention, therefore, has for its object to solve the problem of so arranging a bottom shell that a direct transference of forces to the housing, which alone is adapted to take up such forces, is obtained.

According to the invention, this problem is solved by suspending the bottom shell in a frame which is connected directly to the housing. To the end that, with this arrangement, the bottom shell may be adjustable, it is not just the position of the frame in the housing but the distance of separation between frame and bottom shell that is made variable for purposes of bottom shell adjustment. For this purpose the devices serving for adjustment—it may be, automatic adjustment—are preferably arranged between the bottom shell and the frame. This results in the advantage that the actual frame, which is adapted to take up shocks and is provided for that purpose can be fixedly connected to the housing while the bottom shell is simply supported on the frame in such a way that its level is adjustable. If the distance of separation between the frame and the bottom shell corresponds to the depth of the flange or shroud on the end of the axle journal the assembly and disassembly of the two parts is rendered very simple. The bottom shell is first of all introduced into and raised up in the recess provided in the housing to receive the frame and then the frame is fixed in the housing. The same operations are carried out in reverse order when disassembling the two parts.

It has already been mentioned that, by prefer-

ence, the adjusting means for varying the setting of the bottom shell relatively to the axle journal are arranged between said shell and the frame. This arrangement affords a number of possibilities. Thus for instance, slot-like recesses may be provided in the bottom shell and bars yieldingly pressed into such recesses by adjusting springs, said bars including U-shaped positioning stirrups. After the bottom shell has been introduced the adjusting springs are sufficiently compressed by means of the bars and the U-shaped positioning stirrups associated therewith to enable the frame to be introduced. When this has been done the bars, under the influence of the springs, automatically enter the slot-like recesses on the bottom shell, thus bringing about the automatic adjustment. The arrangement may, however, be such that the springs bear directly on the underside of the bottom bearing shell.

The position of the bottom shell relatively to the frame may also be arranged in many and various ways. If the bottom shell lies wholly between the arms of the frame which rest on lugs on the housing, it is possible so to arrange these bow-shaped frame arms that they are distanced from the surface of the axle journal by a predetermined shock absorbing path. If impulsive forces arise as between the axle journal and the housing of the axle bearing the shock, under damping action, is in part taken by the bottom shell and when the predetermined and permitted shock absorbing path has been traversed the shock is taken by the bow-shaped frame arms which transmit the impulsive forces directly to the housing. The whole bottom shell may, however, be arranged between the axle journal and the frame, this affording the advantage that when the bottom shell is constructed as a lubricating shell the axle journal remains supported on a film of lubricant even during the shocks which are of relatively short duration. With this arrangement the distance of separation between the bottom shell and the frame naturally corresponds to the pre-determined and permissible shock absorbing path.

The fixing of the frame to the housing is conveniently effected by resting one side of the frame on finger-like projections on the housing, the other side being mounted indirectly on lugs in the housing with packing pieces interposed. This admits of the bottom shell being fitted in place in a very simple manner even when the axle journal is provided with a fixed end flange or shroud. The finger-like lugs on the housing are preferably arranged at a level differing from

that of the lugs by the thickness of the packing piece, which thickness is at least equal to the depth of the axle journal end shroud. Thus, by tilting the bottom shell and the frame, both 5 of these members can be introduced past the said end shroud and the frame hung on the finger-like lugs in the housing. The bottom shell and the frame are then brought up to the horizontal, whereupon the packing piece is inserted 10 between the frame and the lugs on the housing and there secured, as, for instance, by connecting it to a part of the frame. Conversely, it is possible to disassemble in an equally simple manner.

There may also be provided, in the housing, 15 ribs, which receive the bottom shell between them and so secure it against axial displacement. The frame is then fixedly attached to the lugs on the housing which carry it so that when the bearing is assembled there is no possibility of 20 any axial displacement at all. In order to ensure that, in the case of axle bearings which are stressed to an unusually high degree, shocks which reach the bottom shell shall be transmitted directly, in the direction of impact, to the housing 25 of the bearing, the frame may be provided with an attachment in the form of a lubricant reservoir, by means of which attachment it is supported in midposition relatively to the housing, preferably against longitudinal ribs thereon. 30 In this case it is advantageous to lock the frame against axial displacement by attaching the aforesaid extension to the housing more particularly to a transverse rib on the same.

In bottom shells whereof the middle part lies 35 between the frame members locking against axial displacement is preferably effected by means of ribs provided in the housing, against which ribs the bowed arms of the frame bear on both sides, so as to lock the said frame and the bottom shell 40 axially. The bottom shell then preferably extends into the space between the ribs on the housing. This makes it possible to augment the working of the bottom shell in the capacity of a lubricant catching member, it being immaterial 45 whether the bottom shell picks up oil delivered solely for this purpose to a point above such bottom shell or whether said bottom shell merely carries off from the surface of the axle journal such lubricant as has not been used up in lubricating said journal by means of the upper liner shell and is flowing back to the lubricant reservoir. 50

In the accompanying drawings which illustrate practical embodiments of the idea according to 55 the invention:

Figs. 1 and 2 are longitudinal and transverse sections through an axle bearing, showing one constructional embodiment of the same wherein the middle part of the bottom shell rests in a 60 hollow on the frame. More particularly the left hand half of Fig. 2 is a section taken on line A—A of Fig. 1 and the right-hand half a section on line B—B thereof, while Fig. 1 is a longitudinal section on line C—C of Fig. 2.

Figs. 3 and 4 show an arrangement of the bottom shell wherein this latter is arranged wholly between the axle journal and the frame. More particularly, Fig. 3 is a vertical longitudinal section through the bearing on line D—D of 65 Fig. 4, while Fig. 4, as regards its left-hand half is a vertical transverse section through the axle bearing, taken on line E—E of Fig. 3, while its right-hand half is a vertical section on line F—F of Fig. 3 with the bottom shell shown in end 70 elevation.

Referring firstly to Figs. 1 and 2, the numeral 1 denotes the axle journal and 2 the end flange or shroud of said journal, which is mounted between a top shell 3 and a bottom shell 4. According to the invention this bottom shell, which preferably 5 has an insert 5 of bearing metal, is suspended in a frame, which is connected directly to the housing 6. This frame consists of two transverse arms 7 and 8 united, to form the frame, by means of two longitudinal bearers 9 and 10. Between the bottom shell 4 and the longitudinal bearers 9 and 10 the devices for automatically adjusting the bottom shell consisting, in the embodiment shown in Figs. 1 and 2 of short, powerful spiral springs 11, seated at one end in spring boxes 12 in the 15 bearers 9 and 10 and, at the other end, in spring boxes 13 in the bottom shell. It is a further feature of the invention that the direct fixing of the frame 7, 8, 9, 10 to the housing is effected by the frame arms 7 and 8 resting at one end directly 20 on finger-like projections 14 on the housing while at the other end they are supported indirectly on lugs 16 on the housing, through the intermediary of packing pieces 15. As is shown particularly in Fig. 1 the bow-shaped arms of the 25 frame are so disposed as to be separated only by a predetermined shock absorbing path 17 from the surface of the axle journal. Shocks occurring as between the axle journal and the housing of the axle bearing are, therefore first imparted, 30 with a certain amount of damping, to the bottom shell 4 and then, after the shock absorbing path 17 has been traversed, directly to the frame members 7 and 8 and by way of the parts 14 and 15, 35 to the housing 6. The arrangement of these parts, as well as their appropriate formation makes it possible for the forces to be transmitted in this way without entailing the disadvantages which apply to the arrangement heretofore proposed. In order that the frame 7, 8, 9, 10 may 40 also be secured in the axial direction, ribs 18 and 19 are provided in the housing and the bowed arms 7 and 8 of the frame bear against these ribs on both sides so as to lock the frame and the bottom shell axially. If the packing piece 15 be 45 fastened to the bowed arm 7, as, for instance, by a split pin 20, which affords a particularly accessible type of fixing, said packing piece will also be properly located. The bottom shell 4 preferably has pan-shaped outriggers or side wings 21 50 which extend into the space 22 between the ribs 18 and 19 of the housing and serve to augment the lubricant catching effect which takes place especially in the vicinity of the edges 23 of the axle box. 55

The new method of fixing the bottom shell makes it extremely simple to disassemble and reassemble the whole bearing. For instance, if the packing piece 15 be removed, after drawing the split pin 20, the frame and the bottom shell can 60 be shifted axially and this releases the connection between the frame arms 7 and 8 and the finger-like projections 14 of the housing. The frame and the bottom shell can thus be brought into an inclined position and drawn, past the axle journal shroud, out of the housing of the axle bearing. As may be supposed, assembly is carried out very simply, in the reverse order.

In the constructional example illustrated in Figs. 3 and 4 the numeral 1 again designates the axle journal and 2 the fixed shroud of the same while 3 and 4 denote the top and bottom shells in which it is carried, the bottom shell preferably including a white metal lining 5. The frame which carries the bottom shell again consists of 70 75

two transverse bows 7 and 8 tied together to make a frame, by means of two longitudinal bars 9 and 10. The frame 7-10 is fixedly located in the housing 6 while the distance of separation between the bottom shell 4 and said frame 7-10 is made variable for the purpose of adjusting said bottom shell. If the separation between the two members corresponds, at least, to the depth of the journal shroud 2, assembly and disassembly are particularly simple. Firstly the bottom shell is introduced and brought into position through the recessed parts 22 of the housing destined to receive the frame 7-10 and then the frame itself is fitted in. Naturally, the same operations are carried out in reversed order when taking out the two parts. Between the bottom shell 4 and the frame 7-10 are arranged the springs 11 used for purposes of automatic adjustment. The bottom shell itself is slotted at 34 and in the slots are received bars 24 which are pressed into engagement by means of the adjusting springs 11 and are provided with U-shaped positioning stirrups 25. If, for instance the parts have to be taken out, the locked screws 26, which fix the frame 7-10 to the lugs 16 on the housing, on which it rests, are first released; then, by pulling down the stirrups 25, the springs 11 are sufficiently compressed to permit the frame 7-10 to be drawn out through the recesses 22 in the housing. The bottom shell then falls of its own accord into the position in which it also can be withdrawn, past the shroud of the axle journal by a simple axial movement. When assembling, the bottom shell 4 is first introduced by way of the recesses 22 in the housing and then the frame 7-10, with the springs 11 compressed, is pushed in. When the springs 11 expand the bars 24, under their influence, enter the slot-like recesses 23 in the bottom shell 4 and in this way the said bottom shell positions itself automatically.

Shocks set up as between the axle journal 1 and the housing 6 are imparted first to the bottom shell 4. Owing to the fact that this latter is arranged wholly between the axle journal 1 and the frame 7-10 and is separated from the frame solely by a predetermined and permissible shock absorbing path, the shocks, after a certain amount of damping while traversing the shock absorbing path, are transferred to the fixed frame, through which they are carried directly to the housing 6, or part 16 thereof. In order that the shocks may be taken up in the actual direction of impact, the frame 7-10 can, as shown in dot and dash lines in Fig. 4, be provided with an attachment 27 in the form of a lubricant reservoir, or sump, by means of which attachment it is supported from the housing; to this end it is preferably guided, after the fashion of a slide, in corresponding recesses 28 in the longitudinal ribs 29 of the housing. In this case fixing in the axial direction is effected, not through the agency of the flange-like extension 30 of the frame 7-10 and the screw 26, but with fixing means 31 which connect the attachment 27 to a transverse rib or other fixed part of the housing 6 of the axle bearing. Since the parts 11, 34, 24 and 25 are not adapted for transmitting axial thrusts from the bottom shell to the frame, ribs or ridges 32, 33 are preferably provided in the housing and the bottom shell 4, more particularly, the pan-shaped outriggers 21 thereof, take in between these ribs. The pan-shaped outriggers preferably, collect the lubricant which for this purpose or in order to lubricate the axle journal, is delivered from the top shell, according to its position, on top of the

bottom shell. In this way the outriggers provide for primary or secondary lubrication of the axle journal.

I claim:

1. In an axle journal bearing, a journal, a one-part housing, a top bearing shell having a continuous bearing shell surface bearing against the axle journal while forming wedge-shaped inlet spaces and a plate-shaped bottom bearing shell for said journal, a frame fixed within the said one-part housing and supporting means for the bottom shell interposed between said bottom shell and said frame, said bottom shell lying between transverse members of the frame, which transverse members rest on supports in the housing. 15

2. In an axle journal bearing, a journal, a one-part housing, a top bearing shell having a continuous bearing shell surface bearing against the axle journal while forming wedge-shaped inlet spaces and a plate-shaped bottom bearing shell 20 for said journal, a frame fixed within the said one-part housing and yielding supporting means for the bottom shell interposed between said bottom shell and said frame, said bottom shell lying between transverse members of the frame, which 25 transverse members rest on supports in the housing.

3. In an axle journal bearing, a journal, a one-part housing, a top bearing shell having a continuous bearing shell surface bearing against the axle journal while forming wedge-shaped inlet spaces, and a plate-shaped bottom bearing shell for said journal, said housing including opposing internal abutments a removable frame including members extending beneath the journal, transversely 35 thereof and supported at their ends by said opposing abutments and supporting means for the bottom shell interposed between said bottom shell and said frame.

4. In an axle journal bearing, a journal, a one-part housing, a top bearing shell having a continuous bearing shell surface bearing against the axle journal while forming wedge-shaped inlet spaces and a plate-shaped bottom bearing shell for said journal, said housing including opposing 45 internal abutments a removable frame including members extending beneath the journal, transversely thereof and supported at their ends by said opposing abutments and supporting means for the bottom shell interposed between said bottom shell and said frame, the abutments on one side of said housing being adapted to fulcrum said frame in addition to locating it transversely of the journal and the abutments on the other side of said housing supporting said frame indirectly 55 through the intermediary of removable packing means.

5. A device according to claim 4 wherein the journal includes an end shroud, the said packing means having a thickness not less than the depth 60 of said end shroud.

6. A device according to claim 4, characterized by the frame hooking at one side of the housing directly on to the finger-like projections in said housing and, at the other side resting on a removable packing piece carried by lugs in said housing. 65

7. A device according to claim 4, characterized by the frame hooking at one side of the housing directly on to finger-like projections in said housing and, at the other side resting on a removable packing piece carried by lugs in said housing, the level of said lugs being below the level of said finger-like projections by the amount of the thickness of said packing piece. 70 75

8. In an axle journal bearing, a journal, a top bearing shell having a continuous bearing shell surface bearing against the axle journal while forming wedge-shaped inlet spaces and a plate-shaped bottom bearing shell for said journal, a one-part housing including internal abutments on opposite walls thereof, a frame having members extending transversely across said housing below the journal and resting on said abutments and means interposed between said frame and the bottom shell for supporting said bottom shell in bearing contact with said journal.
9. In an axle journal bearing, a journal, a top bearing shell having a continuous bearing shell surface bearing against the axle journal while forming wedge-shaped inlet spaces and a plate-shaped bottom bearing shell for said journal, a one-part housing including internal abutments on opposite walls thereof, a frame having members extending transversely across said housing below the journal and resting on said abutments, means interposed between said frame and the bottom shell for supporting said bottom shell in bearing contact with said journal and means associated with said housing for preventing displacement of said frame axially of said journal.
10. In an axle journal bearing, a journal, a top bearing shell having a continuous bearing shell surface bearing against the axle journal while forming wedge-shaped inlet spaces and a plate-shaped bottom bearing shell for said journal, a one-part housing including internal abutments on opposite walls thereof, a frame having members extending transversely across said housing below the journal and resting on said abutments, means interposed between said frame and the bottom shell for supporting said bottom shell in bearing contact with said journal and means associated with said housing for preventing displacement of said frame axially of said journal.
11. In an axle journal bearing, a journal, a top bearing shell having a continuous bearing shell surface bearing against the axle journal while forming wedge-shaped inlet spaces and a plate-shaped bottom bearing shell for said journal, a one-part housing including internal abutments on opposite walls thereof, a frame having members extending transversely across said housing below the journal and resting on said abutments, means interposed between said frame and the bottom shell for supporting said bottom shell in bearing contact with said journal, means associated with said housing for preventing displacement of said frame axially of said journal and further means associated with said housing for preventing displacement of said bottom shell axially of said journal.
12. In an axle journal bearing, a journal, a top bearing shell and a bottom bearing shell for said journal, a housing, including internal abutments on opposite walls thereof, a frame, having members extending transversely across said housing below the journal and resting on the abutments, said frame also including a dependent lubricant sump, means interposed between said frame and the bottom shell for supporting said bottom shell in bearing contact with said journal and means associated with said housing and co-operating with said lubricant sump for locating said frame axially and transversely with respect to said journal.
13. The device of claim 12, including means for locating the bottom shell axially with respect to the journal.
14. In an axle journal bearing, a journal and a housing therefor having opposed internal projections below the level of the journal, a top bearing shell fixed in said casing, a frame supported by said projections and extending therebetween beneath said journal, bearer bars extending parallel to the axis of the journal and yieldingly supported from said frame and a bottom bearing shell supported by said bearer bars in yielding contact with said journal.
15. In an axle journal bearing, a journal and a housing therefor having opposed internal projections below the level of the journal, a top bearing shell fixed in said casing, a frame supported by said projections and extending therebetween beneath said journal, means for locating and retaining said frame in a predetermined fixed position in said housing, bearer bars extending parallel to the axis of the journal and yieldingly supported from said frame, a bottom bearing shell supported by said bearer bars in yielding contact with said journal and means for maintaining predetermined lateral and axial positioning of the bottom shell while permitting limited vertical movement thereof on its yielding supports.
16. In an axle journal bearing, an axle journal, a one-part housing, a top bearing shell and a bottom shell, the said bottom shell having a continuous bearing shell surface, means for supplying lubricant to the axle journal, a frame independent of the one-part housing and separable therefrom, said bottom shell adjustable relatively to the housing, said frame rigidly supported against the housing, said bottom bearing shell supported by said frame, the transverse arms of said frame lying in a direction vertical to the axis of the axle journal and forming abutments for the bottom shell which in its lowest position lies between the transverse arms, the distance of said transverse arms from the axle journal being less than the extent which leads to the loss of the seat of the axle journal in the top bearing shell.
17. In an axle bearing, an axle journal, a one-part housing, a top bearing shell and a bottom shell, said bottom shell having a continuous bearing shell surface, means for supplying lubricant to the axle journal, a frame independent of the one-part housing and separable therefrom, said bottom shell adjustable relatively to the housing, said frame rigidly supported against the housing, said bottom bearing shell supported by said frame, the transverse arms of said frame lying in a direction vertical to the axis of the axle journal and forming abutments for the bottom shell which in its lowest position fills the space between axle journal and transverse arms, the distance of said bottom shell from the transverse arms being less than the extent of movement which leads to the loss of the seat of the axle journal in the top bearing shell.
18. In an axle journal bearing, an axle journal, a one-part housing, a top bearing shell and a lubricating plate-like bottom shell, said bottom shell having a continuous bearing shell surface and bearing against the axle journal while forming wedge-shaped inlet spaces, a frame within the hollow space of said housing and mounted on the said housing but separable therefrom, said bottom shell being yieldably mounted on said frame, said frame rigidly supported against the housing and forming abutments limiting the movement of the bottom shell against frame and housing, the said abutments adapted to main-

tain the seat at the axle journal in the top bearing shell even in the lowest position of the bottom shell, the adjusting path of the bottom shell in the adjusting direction being at least equal to 5 the largest space between the axle journal and the abutments preventing its shock movement, said frame consisting of longitudinal bearers and transverse arms, the latter being adapted to transmit to the housing the shocks exerted by 10 the axle journal and without flexing the bottom shell, means provided within the hollow space of the housing and adapted to prevent a displacement of the frame in the direction of the axis of the axle journal.

15 19. In an axle journal bearing, a journal, a one-part housing, a top bearing shell, a plate-like bottom bearing shell having a continuous bearing shell surface bearing against the axle journal while forming wedge-shaped inlet spaces, 20 a frame mounted directly within the one-part housing, supporting means for said bottom shell, said supporting means being interposed between said bottom shell and said frame and including means to yieldably support and adjust said bottom shell relatively to said journal, said frame rigidly supported against the housing and forming abutments limiting the movement of the bottom shell against frame and housing, the said abutments adapted to maintain the seat at the 25 axle journal in the top bearing shell even in the lowest position of the bottom shell, the adjusting path of the bottom shell in the adjusting direction being at least equal to the largest space between the axle journal and the abutments preventing its shock movement, said frame consisting of longitudinal bearers and transverse arms, the latter being adapted to transmit to the housing 30 the shocks exerted by the axle journal and without flexing the bottom shell due to the yieldable means, the space between the journal and abutments limiting its shock movement being at most equal to the greatest adjusting path of the lower brass in the adjusting direction, means provided within the hollow space of the housing and adapted to prevent a displacement of the frame in the direction of the axis of the axle journal.

35 20. In an axle journal bearing, a journal, a one-part housing, a top bearing shell, a bottom plate-like bearing shell having a continuous bearing shell surface bearing against the axle journal while forming wedge-shaped inlet spaces, a frame mounted rigidly within the said one-part housing, yielding supporting means for said bottom shell interposed between said bottom shell and said frame, means associated with said yielding supporting means for permitting limited shock absorbing movement of the axle journal relatively to the frame, the adjusting path of the bottom shell in the adjusting direction being at 40 least equal to the largest space between the axle journal and the abutments preventing its shock movement, said frame rigidly supported against the housing and forming abutments limiting the movement of the bottom shell against frame and housing, the said abutments adapted to maintain the seat at the axle journal in the top bearing shell even in the lowest position of the bottom shell, the adjusting path of the bottom shell in the adjusting direction being at 45 least equal to the largest space between the axle journal and the abutments preventing its shock movement, said frame consisting of longitudinal bearers and transverse arms, the latter being adapted to transmit to the housing the shocks exerted by the axle journal and without flexing the bottom shell, means provided within the hollow space of the housing and adapted to prevent a displacement of the frame in the direction of the axis of the axle journal.

50 21. In an axle journal bearing, a journal, a one-part housing, a top bearing shell, a plate-like bottom bearing shell having a continuous bearing shell surface bearing against the axle journal while forming wedge-shaped inlet spaces, a frame fixed within the said one-part housing, yielding supporting means for the bottom shell interposed between said bottom shell and said frame, said bottom shell being located wholly between the journal and the frame and including a part normally spaced from said frame by a pre-determined gap, said frame rigidly supported against the housing and forming abutments limiting the movement of the bottom shell against frame and housing, the said abutments adapted to maintain the seat at the axle journal in the top bearing shell even in the lowest position of the bottom shell, the adjusting path of the bottom shell in the adjusting direction being at 55 least equal to the largest space between the axle journal and the abutments preventing its shock movement, said frame consisting of longitudinal bearers and transverse arms, the latter being adapted to transmit to the housing the shocks exerted by the axle journal and without flexing the bottom shell, means provided within the hollow space of the housing and adapted to prevent a displacement of the frame in the direction of the axis of the axle journal.

55 22. In an axle journal bearing, a journal, a one-part housing, a top bearing shell, a plate-like bottom bearing shell having a continuous bearing shell surface bearing against the axle journal while forming wedge-shaped inlet spaces, a frame fixed within the said one-part housing, yielding supporting means for the bottom shell interposed between said bottom shell and said frame, said bottom shell being located wholly between the journal and the frame and including a part normally spaced from said frame by a pre-determined gap, said frame rigidly supported against the housing and forming abutments limiting the movement of the bottom shell against frame and housing, the said abutments adapted to maintain the seat at the axle journal in the top bearing shell even in the lowest position of the bottom shell, the adjusting path of the bottom shell in the adjusting direction being at 60 least equal to the largest space between the axle journal and the abutments preventing its shock movement, said frame consisting of longitudinal bearers and transverse arms, the latter being adapted to transmit to the housing the shocks exerted by the axle journal and without flexing the bottom shell, means provided within the hollow space of the housing and adapted to prevent a displacement of the frame in the direction of the axis of the axle journal.
